UNITED STATES PATENT OFFICE.

HENRY C. HENO AND ROBERT GREENLEAF, OF PITTSFIELD, MASSACHUSETTS.

CIRCLE-SAW.

No. 902,656.

Specification of Letters Patent.

Patented Nov. 3, 1908.

Application filed March 21, 1907. Serial No. 363,715.

To all whom it may concern:

Be it known that we, HENRY C. HENO and ROBERT GREENLEAF, citizens of the United States, residing at Pittsfield, in the county of 5 Berkshire and State of Massachusetts, have invented a new and useful Improvement in Circle-Saws, of which the following is a specification.

This invention relates to a circle saw and 10 the object of the invention is a sawing machine by means of which circular wooden disks may be cut out such as bottoms of tubs, beaters, etc.

It has heretofore been common to cut out 15 by hand wooden disks which were too large to be handled by band saws, and from one to two hours is often required in order to cut out one piece.

With our invention, a wooden disk having 20 a diameter from six feet to eleven feet can be readily cut within a few minutes time and practically without the expenditure of any manual labor other than that required to control an electric motor. The machine 25 is also adapted for use in connection with wood bottoms several inches in thickness.

The invention consists of a truck, a portable sawing machine thereupon, and means 30 for automatically moving said truck in a circle upon the material being operated upon.

In the accompanying drawings:—Figure 1 is a side view of the machine, a portion of a wooden bottom being shown in section. Fig. 35 2 is an end view of the machine, a portion of the wooden bottom being shown in cross-section.

In these drawings A represents the material being operated upon by the machine, and B represents the truck, mounted upon the 40 casters C. The truck is also mounted upon a wheel C' which is fixed upon a shaft C², said shaft being journaled in the frame B.

A rod D is held in bearings D' carried by the truck B and the rod D has its outer end 45 portion clamped to a socket pin D² by means of a set screw D³. The socket pin D² is fitted into a recess provided for it in the true center of the disk to be cut.

An upright guide-frame E is carried at one 50 end of the truck B and in said frame works a cross-head E' which is moved vertically by a pitman E² pivoted at its upper end to a wheel E³. The lower end of the cross-head E' carries a saw E⁴ which works through an angled gage E⁵, the gage being carried by the 55 lower portion of the upright guide-frame E.

The wheel E³ is mounted upon a shaft E⁸ upon which is fixed pulleys E⁶ and E⁷. A handle E⁹ is also fixed to the side of the 60 guide-frame E.

A motor F of any suitable type is mounted upon the truck B and a belt F' transmits rotary motion from the motor to the pulley E⁶. A belt G runs over the pulley E⁷ and also over the pulley G'. The pulley G' is mounted upon a suitable worm shaft H', the worm to which engages a gear wheel H carried by the shaft, C².

The operation of the above described parts are as follows:—The diameter of the 70 circle to be cut is fixed by the length of the rod D measuring the distance from the socket D² to the saw E⁴. As soon as the motor is started the saw will be reciprocated through the movement of the cross-head E⁷⁵ and pitman E² and at the same time the truck B will commence its travel in a circle about the socket pin D², the travel of the truck being caused by engagement of the gear H and the worm gear H'. The rotary motion transmitted from the motor to the shaft E⁸ is transmitted through the pulley E⁷, belt G, pulley G', worm gear H', gear H, shaft C², to the wheel C'. Should the rate of travel at any time tend to exceed the cutting 85 rate of the saw, it can be checked by the operator grasping the handle E⁹, upon which he is supposed to keep one hand during the operation of the machine. The motor can of course be started and stopped in the usual 90 manner by arranging an electrical switch at any point convenient to the operator.

Having thus described our invention, what we claim as new and desire to secure by 95 Letters Patent, is:—

1. A device of the kind described comprising a truck adapted to move upon the work operated upon, a saw carried by said truck, means carried by the truck for reciprocating the saw and means for imparting a 100 circular movement to the truck.

2. A circle saw of the kind described comprising a truck, a reciprocating saw carried by the truck, means carried by the truck for reciprocating the saw, means for imparting 105 positive motion to the truck, and means for guiding the truck about the center of the work being operated upon.

3. A device of the kind described comprising a wheeled truck, means for moving said truck in a circle, an upright carried by an end 110 of the truck, a handle carried by said upright,

a driven wheel carried by said upright, a pitman secured to the wheel, and a saw blade connected to said pitman.

4. A device of the kind described comprising a truck, a saw carried by the truck, a socket pin, said pin being carried by the work operated upon by the saw, the said truck being also carried by said work, a rod

adjustably connected to said socket pin, and means connecting the rod to the truck as and for the purpose set forth. 10
